(57) CLAIM

The ornamental design for a tennis vest, as shown and described.

DESCRIPTION

FIG. 1 is a front elevation view of our new tennis vest design, the rear elevation view being a mirror image thereof;

FIG. 2 is a right side elevation view of FIG. 1, the left side elevation view being a mirror image thereof;

FIG. 3 is a top plan view of FIG. 1;

FIG. 4 is a bottom plan view of FIG. 1; and,

FIG. 5 is a front and right side perspective view of the design shown in use.

The broken lines shown in the drawings illustrate environment and form no part of the claimed design.
